UNITED STATES PATENT OFFICE

CHESTER I. HALL, OF FORT WAYNE, INDIANA, ASSIGNOR TO GENERAL ELECTRIC COMPANY, A CORPORATION OF NEW YORK

ELECTRICALLY-WOUND CLOCK

Application filed April 12, 1928. Serial No. 269,514.

My invention relates to a constant torque motive mechanism which is suitable for general application but which is particularly adapted for use in spring driven clock movements where a small electric motor is employed for winding the spring.

The time keeping qualities of the ordinary hand wound spring driven clock movement is impaired by reason of the fact that the 10 clock escapement is required to regulate the speed between wide limits of the main spring tension. In the eight day clock for example, when the spring is fully wound, the escapement mechanism is subjected to considerably more tension than exists when the spring is nearly unwound. As a result the beat of the escapement tends to vary somewhat with the tension of the main spring. This varying condition may be compensated for to 15 some extent but at the expense of added complications and cost. To avoid the conditions above mentioned it has been proposed to maintain the clock spring wound to a substantially constant tension by automatic 20 means, such as an electric motor, together with means dependent upon the condition of the spring for controlling the motor.

My invention relates to improvements in devices of the last mentioned group and its 25 principal object is to provide a simple, inexpensive but reliable mechanism for maintaining the clock spring wound to a very uniform tension. In carrying my invention into effect I provide means responsive to the counter-torque of the main spring for controlling the winding torque transmitted thereto from the winding motor. In the preferred form of my invention a worm gear is provided between the winding motor and the spring 30 through which the counter-torque is transmitted. The motor is of the conventional induction, disc, alternating current type, but has its stator element pivotally mounted. An 35 adjustable helical spring serves to normally hold the stator in the maximum torque operating position. When the counter-torque of the main spring reaches a predetermined value, however, the torque required to rotate the disc armature is such as to overcome the 40 force of the helical spring and the stator

shifts into a reduced torque position. The disc then stops or keeps moving just enough to maintain the tension on the main spring substantially constant.

The features of my invention, which are 45 considered novel and patentable, are pointed out in the appended claims. The invention itself, however, will best be understood by reference to the following specification when considered in connection with the accompanying drawing in which Fig. 1 is an expanded perspective view of the invention applied to a clock.

Fig. 2 is an enlarged view of the rewinding motor, illustrating the pivotally mounted 50 stator.

Fig. 3 is a detail view illustrating the normal operating position of the field poles and in dotted lines, the possible position when the counter-torque of the spring has reached 55 a predetermined value.

Referring to Fig. 1, 10 indicates the main spring of a clock mechanism having its outer end attached to a gear 11 and driving the minute hand 12 by means of pinion 13 60 and shaft 14. The hour hand 12' is driven through a set of back gears 15. A standard spring escapement 16 regulates the movement of shaft 14 through pinion 17 and gear 18. The inner end of spring 10 is attached 65 to shaft 19 by means of which it is rewound. Shaft 19 is driven by motor 20 through a suitable set of reduction gears 21.

Motor 20 includes a U-shaped magnetic frame 22 mounted on pivots 23 and 24. A 70 core 25, having wound thereon a coil 26, is attached to one side of the frame 22, and a pole-piece 27 having a shorted coil 28 thereon is attached to the other side. A disc 29 of 75 conducting material extending into the gap between 25 and 27 and mounted on shaft 30 is caused to rotate when coil 25 is energized by alternating current. A worm 34 mounted on shaft 30 engages the first gear of gear train 21 and constitutes an irreversible 80 drive, so that in case the motor stops the spring may still drive the clock mechanism for a considerable time. The torque exerted by disc 29 depends upon the position of the coil 28 on pole 27. The alternating 85

flux passing through the disc is converted into a shifting flux by the coil 28 and the amount of shift, tangential to the direction of rotation, determines the torque exerted by disc 29. When the spring 10 becomes wound the force required to turn the disc becomes greater. Helical spring 31 is however adjusted, by means of clamping nut 33, to hold frame 22 in its normal position against stop 32 with a force which when multiplied through the reduction gearing amounts to the maximum desired counter-torque of the main spring. Any tendency to wind the spring to a greater tension causes the poles to shift from the normal position in a direction opposite to the direction of rotation of the disc, and into a position such as indicated by dotted lines in Fig. 3. The coil 28 is then in a position causing less shifting of the flux tangential to the disc 29 and, therefore, less torque exerted by the disc 29. This displacement of course continues until the force of spring 31 is balanced against the counter-torque of the main spring through the gearing.

In accordance with the provisions of the patent statutes, I have described the principle of operation of my invention, together with apparatus which I now consider to represent the best embodiment thereof, but I desire to have it understood that the apparatus shown and described is only an illustration and that the invention may be carried out by other means.

What I claim as new and desire to secure by Letters Patent of the United States is:—

1. An induction disc motor including a rotatable disc armature and a movable stator arranged to control the torque exerted by said armature, and resilient means tending to maintain the stator in a maximum torque producing position but yieldable in response to the motor torque to allow the stator to move to a lower torque producing position, whereby the position of said stator is varied to maintain constant the torque exerted by said armature.

2. In apparatus of the character described, an induction disc motor comprising a rotatively mounted armature and a pivotally mounted stator having thereon for movement therewith a shaded pole element the position of which determines the torque exerted by said armature, and means responsive to the motor torque for controlling the position of said stator.

3. An electric motor including a disc armature arranged to wind a driving spring, a pivotally mounted stator, a spring tending to hold said stator in the maximum-torque operating position and arranged to allow said stator to move into a reduced-torque operating position when the counter-torque of the driving spring has reached a predetermined value.

4. In apparatus of the character described an induction motor comprising a rotatably mounted induction disc armature and a stator element having an energizing winding and shaded pole for producing a shifting flux through said disc, said stator element being pivoted for limited rotation about an axis parallel to the axis of rotation of said disc, a spring adapted to hold said stator element in a position where the direction of flux shift corresponds to the direction of movement of said disc when the motor torque is small and to yield in response to an increase in motor torque to permit said stator to move into a position where the direction of flux shift is at an angle to the direction of movement of said disc.

In witness whereof, I have hereunto set my hand this 9th day of April, 1928.

CHESTER I. HALL.
